(57) **CLAIM**

The ornamental design for a bowl, as shown and described.

DESCRIPTION

FIG. 1 is a top plan view of a bowl.

FIG. 2 is a side elevational view of the bowl of FIG. 1, the opposite side and ends being identical thereto.

FIG. 3 is a bottom plan view of the bowl of FIG. 1; and, FIG. 4 is a perspective view of the bowl of FIG. 1.
